KEY HOLDER

Joseph G. Lipic, Jr., St. Louis, Mo.

Application November 4, 1935, Serial No. 48,103

2 Claims. (Cl. 59—96)

This invention relates generally to key holders, and more specifically to an improved key holder which includes as a part thereof means for indexing a particular key of a plurality of keys held in assembled relation by the improved key holder, so that said particular key may be readily selected from the assembled keys for use, the predominant object of the invention being to provide an improved key holder of this type which is capable of performing its intended function in a highly efficient manner.

As is generally known, many persons carry in their possession groups of keys and frequently in such a case one of these keys is considered more important than the others because of the frequent use to which it is put, or for other reasons. This more important key may be an automobile key, a house door key, or a key to a drawer, locker, etc. It is considered quite an inconvenience and annoyance for a person to be compelled to search through a group of keys for a desired key, and this is particularly true when such search must be gone through repeatedly during the day. Also such search for a particular key is of increased inconvenience and annoyance when it must be made in darkness, as in the case of an automobile key or door key.

The improved key holder disclosed herein includes means for indexing an important or frequently used key so that it may be readily selected from a group of keys retained by the key holder without the necessity of searching through the group of keys for the desired key. Thus the inconvenience and annoyance heretofore encountered in frequently selecting a particular key from a group of keys carried by a person are entirely eliminated, and because the selection may be made entirely by touch such selection may be made in darkness as readily as in daylight.

Fig. 1 is a side elevation of the improved key holder, with keys associated therewith.

Fig. 2 is a view similar to Fig. 1, but showing the indexing element of the improved key holder in section.

Fig. 3 is a view showing the key holder illustrated in Fig. 2 in plan.

Fig. 4 is a sectional view of a fragment of the improved key holder.

Fig. 5 is a fragmentary view illustrating a modified form of the invention.

In the drawing, wherein are shown for the purpose of illustration, merely, two embodiments of the invention, A designates the improved key holder generally. The key holder A includes an indexing element 1 which receives an important or frequently used key, such a key being designated by the reference character K in the drawing.

The particular indexing element shown in the drawing comprises an elongated section of celluloid or other suitable material which is of slightly greater length than the average key, the indexing element illustrated being substantially round in cross-section, although obviously the indexing element may be of any desired cross-sectional shape. The indexing element 1 has formed therein a slot 2 that extends longitudinally thereof, which slot is open at one end of the indexing element and extends entirely through said element transversely thereof from one to the opposite side for a portion of the length of the indexing element measured from the end thereof at which the slot 2 is open. At one side of the indexing element 1 the slot 2 terminates a relatively short distance inwardly from the end of the element at which the slot is open, as shown at 2^a in Fig. 2, but at the opposite side of the element 1 the slot continues longitudinally of said element to a point just short of the end of said element 1 which is located opposite to the end thereof at which the slot 2 is open, as indicated at 2^b in Fig. 2. Thus a slot is provided in the indexing element which extends entirely through a portion of the element transversely thereof, so that in this portion of the element the slot is open at an end of the element and at opposite sides thereof, while in another portion of the indexing element the slot extends only a part of the transverse distance through the element, so that in this portion of the element the slot is open only at one side of the element.

Formed in the portions of the indexing element 1 located at opposite sides of the slot 2, at points located inwardly a slight distance from the end of said element at which the slot 2 is open, is a pair of aligned openings 3. These aligned openings receive a pivot member 4 which is extended across the slot 2 and passes through an aperture K' formed in the key K so as to pivotally attach said key to said indexing element, the portion of the key in which the opening is formed being located within the slot 2. The pivot member 4 includes a sleeve 5 which is provided at one end with a head 5', said sleeve being internally screw-threaded and being disposed in the aligned openings 3 with the head 5' thereof contacting with the outer face of the indexing element 1 at one side thereof. Associated with the sleeve 5 is a screw 6 which is provided with a head 6', the screw-threaded shank of said screw being threaded into the sleeve 5 and its head being 55

in contact with the outer face of the indexing element at a point opposite to the location of the head 5' of the sleeve 5.

Thus the elements 5 and 6 of the pivot member 4 may draw the portions of the indexing element 1 at opposite sides of the slot 2 into close frictional contact with the key K, so that the key is supported by the indexing element for controlled pivotal movement. Therefore the key K 10 may be moved to the position shown in Fig. 1, where it is received and enclosed in the slot 2 in the manner of a blade in the handle portion of a pocket knife, or said key may be moved about the pivot member 4 to the extended position shown in Fig. 2, when it is desired to use the key.

Formed through the indexing element 1, at a point adjacent to the end thereof opposite to the end of said element at which the slot 2 is 20 open, is a transverse opening 7. Extended through this opening is a flexible key-retaining element 8, which in Figs. 1, 2, and 3 constitutes a section of chain whose ends are connected together at 8'. This section of chain is extended 25 through the openings K^a formed through the keys K^b, said keys K^b being a group of assembled keys of which the key K is a part. Thus the keys K^b are maintained in assembled relation with the key K through the instrumentality of the indexing element 1, the entire assemblage of keys being connected together in such flexible relation as to be capable of being conveniently handled and carried about in a pocket or purse.

In the use of the improved key holder disclosed 35 herein a person may readily and conveniently locate his frequently used key even in darkness by merely grasping the indexing element 1, and by an operation as simple as opening a blade of a pocket knife the key may be placed in position for use. Thus the annoyance and inconvenience of repeatedly searching through a group 40

of keys for a frequently used key are entirely eliminated in the use of the improved key holder.

Instead of employing the flexible chain 8 for retaining the secondary keys (designated K^b in Figs. 1, 2, and 3), a split key ring 9 of ordinary 5 construction may be employed for this purpose as shown in Fig. 5. As shown in this view, the split key ring 9 is extended through the opening 7 and the secondary keys 10 are received by said split key ring in the usual manner. 10

I claim:

1. A key holder comprising an element having a slot formed longitudinally therein which is open at one end of the element and at opposite sides thereof, said element being of solid formation at its other end, a pivot member extended across said slot at the end of the element where the slot is open and adapted to pivotally attach a key to the element so that said key may be swung about said pivot member to a position 20 within the slot or to a position extended outwardly beyond the end of the element where said slot is open, and means connected to said element at its solid end for receiving one or more other keys. 25

2. A key holder comprising an element having a slot formed longitudinally therein which is open at one end of the element and at opposite sides thereof, said element being of solid formation at its other end and said slot being longer at 30 one side of the element than at the opposite side thereof, a pivot member extended across said slot at the end of the element where the slot is open and adapted to pivotally attach a key to the element so that said key may be swung 35 about said pivot member to a position within the slot or to a position extended outwardly beyond the end of the element where said slot is open, and means connected to said element at its solid end for receiving one or more other keys. 40
